[57] **ABSTRACT**

An image generation-transfer cassette forms an image on a cooperating member. The image generation-transfer cassette includes a cassette body, an image generation medium disposed in the cassette body, and an intermediate transfer recording medium disposed in the cassette body to face the image generation medium. The intermediate transfer recording medium has a substrate layer and an image receiving layer releasably disposed on the substrate layer. The image generation medium generates the image onto the image receiving layer, and the image receiving layer is transferred onto the cooperating member.

FIG. 3

IMAGE GENERATION-TRANSFER CASSETTE

This application claims the benefit of Application No. 10-276694, filed in Japan on Sep. 30, 1998, which is hereby incorporated by reference.

BACKGROUND OF THE INVENTION

1. Field of the Invention

The invention relates to an image generation-transfer system and, more particularly, to an image generation-transfer cassette that generates an image on a receiving layer of an intermediate image transfer recording medium and transfers the receiving layer onto a cooperative member simultaneously.

2. Discussion of the Related Art

Various techniques are known for transferring an image onto a cooperative member (i.e., an object to receive the image). For example, Japanese Laid-Open Patent Application Nos. 62-238791 and 4-133793 disclose methods for transferring an image on a receiving layer of an intermediate image transfer recording medium onto a cooperative member. Generally, in the disclosed methods, an intermediate image transfer recording layer is generated having an image receiving layer releasably disposed on a substrate layer. A dye transferred image is then formed on the image receiving layer by using image generation sheet (i.e., an image generating process). Subsequently, the image on the image receiving layer is transferred onto a cooperative member (i.e., an image transfer process). Accordingly, an image can be formed on a cooperative member having a surface with poor dyeability or asperity. Further, the image quality is less affected by the asperity and texture of the surface of the cooperative member.

However, in the conventional method, the two separate processes (i.e., the image generating process and the image transfer process) are required. Thus, the conventional methods suffer from limited efficiency.

SUMMARY OF THE INVENTION

Accordingly, the present invention is directed to an image generation-transfer cassette that substantially obviates one or more of the problems due to limitations and disadvantages of the related art.

An object of the invention is to provide an image generation-transfer cassette that can generate an image on the image transfer recording layer and substantially simultaneously transfer the image to a cooperative member.

Additional features and advantages of the invention will be set forth in the description which follows, and in part will be apparent from the description, or may be learned by practice of the invention. The objectives and other advantages of the invention will be realized and attained by the structure particularly pointed out in the written description and claims hereof as well as the appended drawings.

To achieve these and other advantages and in accordance with the purpose of the present invention, as embodied and broadly described, an image generation-transfer cassette for forming an image onto a cooperative member including a cassette body; an image generation medium disposed in the cassette body; an intermediate transfer recording medium disposed in the cassette body to face the image generation medium, the intermediate transfer recording medium having a substrate layer and an image receiving layer releasably disposed on the substrate layer, wherein the image genera-

tion medium generates the image onto the image receiving layer, and wherein the image receiving layer is transferred onto the cooperating member.

It is to be understood that both the foregoing general description and the following detailed description are exemplary and explanatory and are intended to provide further explanation of the invention as claimed.

BRIEF DESCRIPTION OF THE DRAWINGS

10 The accompanying drawings, which are included to provide a further understanding of the invention and are incorporated in and constitute a part of this specification, illustrate embodiments of the invention and together with the description serve to explain the principles of the invention. In the drawings:

FIG. 1 is a schematic diagram of the image generation-transfer cassette according to an embodiment of the present invention.

20 FIGS. 2A-2D are sectional views showing the image generation-transfer cassette according to an embodiment of the present invention.

FIG. 3 is a schematic view showing another embodiment of the image generation-transfer cassette of the invention.

DETAILED DESCRIPTION OF THE PREFERRED EMBODIMENTS

Reference will now be made in detail to the preferred embodiments of the present invention, examples of which are illustrated in the accompanying drawings.

The structure of an image generation transfer cassette in accordance with an embodiment of the present invention will now be described with reference to FIG. 1.

As shown in FIG. 1, the image generation-transfer cassette 10A comprises a cassette body 11 and an intermediate transfer recording medium 30. Here, the cassette body 11 includes a case to contain an image generation sheet 20 and the intermediate transfer recording medium 30. In the illustrated embodiment of FIG. 1, the cassette body 11 further includes a first roll 12 on which is wound the portion of the image generation sheet 20 that has not yet been used, a second roll 13 on which is wound the portion of the image generation sheet 20 that has been used, and guide rollers R1, R2 that guide the image generation sheet. Moreover, the cassette body 11 includes rolls 14, 15 and guide rollers R3, R4, R5, R6 for conducting the intermediate transfer recording medium 30. In addition, the cassette body 11 defines a first opening space 11a in which a thermal head 41 (as an image generating device) is disposed to transfer the image 30 from the image generation sheet 20 to an image receiving layer of the intermediate transfer recording medium 30. Furthermore, the cassette body 11 defines a second opening space 11b in which a heat roller 42 (as an image transfer device) is disposed to transfer the image generated on the image receiving layer of the intermediate transfer recording layer 30 to the cooperating member 50.

The image generation transfer cassette 10A is generally used with an image generation-transfer apparatus 40A. The image generation-transfer apparatus 40A comprises the thermal head 41, the heat roller 42, and the platen roller 43. The cassette 10A is attached to the image generation-transfer apparatus 40A such that the first opening space 11a is positioned to receive the thermal head 41, and the second opening space 11b is positioned to receive the heat roller 42. Additionally, rolls 13, 15 are connected with a driving system of the image generation-transfer apparatus 40A for winding-up the image generation sheet 20.

Image generation sheet **20** generates an image on the image receiving layer of the intermediate transfer recording medium **30**. Here, a heat transfer sheet is preferably used. The image generation sheet **20** is disposed to face the intermediate transfer recording medium **30** at the position where the thermal head **41** is disposed. The image is then transferred by the intermediate transfer recording medium **30** to a position where the heat roller **42** is disposed. Here, the image receiving layer of the intermediate transfer recording medium **30** faces to a platen roller **43** that guides the cooperating member **50** with respect to the second opening **11b**. The image is thus transferred onto the cooperating member **50**.

The operation of the image generation sheet **20**, the intermediate transfer recording medium **30**, and the image generation transfer cassette **10A** of the embodiment of FIG. 1 will now be described in detail with reference to FIGS. 2A-2D.

FIG. 2A is a sectional view of the image generation layer **20** used in the embodiment of FIG. 1. As shown in FIG. 2A, the image generation sheet **20** comprises a layer of sublimable dye layer **22** on one side of the substrate film **21**, a thermal fusion type black ink layer **23**, and an adhesive layer **24**. The sublimable dye layer **22** includes a yellow dye layer **22Y**, a magenta dye layer **22M**, a cyan dye layer **22C**, and a black dye layer **22Bk**. Here, an image that is generated using the image generation sheet **20** by thermal transfer has excellent gradation quality, and an image generated by using the thermal fusion type black ink layer **23** is suitable for optical character recognition (OCR).

The adhesive layer **24** includes a first adhesive layer **24a** disposed on the sheet substrate **21**, and a second adhesive layer **24b** is disposed on the first adhesive layer **24a**. The first adhesive layer **24a** is formed of a material that is suitable to be adhered to the surface of the cooperative member **50**, whereas the second adhesive layer **24b** is suitable to be adhered to the receiving sheet **34** of the intermediate transfer recording medium **30**. Thus, the second adhesive layer **24b** is generally formed of a different material than the first adhesive layer **24a**. Additionally, a release layer (not shown) can be used between the substrate sheet **21** and the adhesive layer **24**. The release layer assists the release of the adhesive layer **24** from the sheet substrate **21**. Also, a rubbing layer may be provided on the opposite side of the adhesive layer **24** with respect to the sheet substrate **21**, thereby improving the sliding ability between the image generation sheet **20** and the thermal head **41**.

FIG. 2B is a sectional view of the intermediate transfer recording layer **30** used in the embodiment of FIG. 1. The intermediate transfer recording medium **30** includes a medium substrate **31**, a releasing layer **32**, a released-off layer **33**, and an image receiving layer **34**. Alternatively, if the medium substrate **31** is releasable, the releasing layer **32** is not needed. The released-off layer **33** assists the release of the image receiving layer **34** with the released-off layer **33** from the medium substrate **31**. Here, the released-off layer **33** also acts as a protective layer to prevent the quality of the image transferred on the cooperative member **50** from being affected by surroundings, fingerprints or other contaminants. Image receiving layer **34** receives the dye of sublimable dye layer **22** of the image generation sheet **20**, and the image **22T** is generated.

FIG. 2C is a sectional view showing intermediate transfer recording medium sheet **30** having an image **22T** and adhesive layer **24T** composed thereon. The image **22T** and the adhesive layer **24T** are composed as follows. The sub-

limable dyes of the image generation sheet **20** of yellow **22Y**, magenta **22M**, cyan **22C**, and black **22Bk** are transferred consecutively to the intermediate transfer recording layer **30**, and then the thermal fusion type black ink layer **23** is transferred to make the image **22T**. Next, the adhesive layer **24** is transferred on the image receiving layer **34**. In the case, the second adhesive layer **24b** of the adhesive layer **24** adheres directly to the image receiving layer **34**. Also, the first adhesive layer **24a** is easily released from the releasing surface of the sheet substrate **21** to the outermost surface of the transfer layer **30T** after the second adhesive layer **24b** was transferred thereon.

As shown in FIG. 2D, the transferred layer **30T** having the image **22T** on the receiving layer **34** is released from the medium substrate **31** and transferred onto the cooperative member **50**. As a result, the image layer **30G** is formed on the cooperative member **50**.

FIG. 3 is a schematic view showing another embodiment of the image generation-transfer cassette of the invention.

The image generation-transfer cassette of FIG. 3 does not have a roller for winding up the intermediate transfer recording medium sheet **30** after the image is transferred to the intermediate transfer recording medium sheet **30**. Here, the embodiment of FIG. 3 includes nipping rollers **R11**, **R12** that nips the intermediate transfer recording medium sheet **30** when the transfer layer **30T** of the intermediate transfer recording medium **30** is transferred to the cooperative member **50**. Also, the image generation-transfer apparatus includes the nipping rollers **R13**, **R14** that nips the intermediate transfer recording medium sheet **30** when the transfer layer **30T** of the intermediate transfer recording medium is transferred to the cooperative member **50**, and cutter **44** to cut the intermediate transfer recording medium sheet **30** after the transfer layer **30T** is transferred.

Of course, additional variations and modifications of the invention can be implemented. In exemplary alternative embodiments, the image generation-transfer apparatus may have a device that winds up the intermediate transfer recording medium after the transfer step of the transfer layer is finished. Also, the sublimable dye layer and the heat fusion type black layer do not both need to be used; one of the two can be selected according to specific application. Further, the cassette body may be configured to suit the image generation-transfer apparatus. For example, the shape, size, specific location or other characteristics of the first and the second opening spaces are changeable according to the arrangement in the image generation-transfer apparatus.

As described above, with the image generation-transfer cassette according to the invention, an image are generated and transferred at substantially the same time. For example, according to the embodiments described above, the cassette body contains the image generation sheet and intermediate transfer recording layer such that the image-generating step and the transfer step are completed substantially simultaneously. As a result, the image generation-transfer method is more efficient.

It will be apparent to those skilled in the art that various modifications and variations can be made in the image generation-transfer cassette of the present invention without departing from the spirit or scope of the invention. Thus, it is intended that the present invention cover the modifications and variations of this invention provided they come within the scope of the appended claims and their equivalents.

What is claimed is:

1. An image generation-transfer cassette for forming an image onto a cooperating member, the image generation-transfer cassette comprising:

a cassette body;
 an image generation medium disposed in the cassette body;
 an intermediate transfer recording medium disposed in the cassette body to face the image generation medium, the intermediate transfer recording medium having a substrate layer and an image receiving layer releasably disposed on the substrate layer, wherein the image generation medium generates the image onto the image receiving layer, and wherein the image receiving layer is transferred onto the cooperating member.

2. The image generation-transfer cassette according to claim 1, wherein the image generation medium includes a substrate portion and a colorant layer on the substrate portion, the colorant layer having at least one color layer to generate the image.

3. The image generation-transfer cassette according to claim 1, wherein the image generation medium further includes an adhesive layer formed on the substrate layer to facilitate the image receiving layer being adhered to the cooperative member when the image is transferred onto the cooperative member.

4. The image generation-transfer cassette according to claim 1, wherein the cassette body defines a first opening for receiving an image generating device to generate the image on the image receiving layer of the intermediate transfer recording medium.

5. The image generation-transfer cassette according to claim 4, wherein the image generating device includes a thermal head and the first opening is adjusted to receive the thermal head.

6. The image generation-transfer cassette according to claim 4, wherein the cassette body defines a second opening through which the image formed on the image receiving layer of the intermediate transfer recording medium is transferred to the cooperative member.

7. The image generation-transfer cassette according to claim 1, wherein the cassette body defines a second opening through which the image formed on the image receiving layer of the intermediate transfer recording medium is transferred to the cooperative member.

8. The image generation-transfer cassette according to claim 7, wherein the second opening receives a heat roller to transfer the image receiving layer having the image to the cooperative member.

9. The image generation-transfer cassette according to claim 1, wherein the intermediate transfer recording medium further includes a releasing portion disposed between the substrate layer and the image receiving layer to facilitate the separation of the image receiving layer from the substrate layer of the intermediate transfer recording medium.
